H. W. OSTER.
DIE STOCK.
APPLICATION FILED NOV. 23, 1914.

Patented Aug. 17, 1915.

UNITED STATES PATENT OFFICE.

HERMAN W. OSTER, OF CLEVELAND, OHIO, ASSIGNOR TO THE OSTER MANUFACTURING COMPANY, OF CLEVELAND, OHIO, A CORPORATION OF OHIO.

DIE-STOCK.

1,150,449.

Specification of Letters Patent. Patented Aug. 17, 1915.

Application filed November 23, 1914. Serial No. 873,433.

To all whom it may concern:

Be it known that I, HERMAN W. OSTER, a citizen of the United States, residing at Cleveland, in the county of Cuyahoga and 5 State of Ohio, have invented a certain new and useful Improvement in Die-Stocks, of which the following is a full, clear, and exact description.

This invention is an improvement in the 10 kind of receding die stocks in which there is a work-holder, a die-carrier, which, as threads are being cut, not only turns but moves longitudinally relative to the work-holder, a cam plate for controlling the position 15 of the dies, and an inclined member which controls the position of the cam plate and which rotates with the die-carrier but does not move endwise relative to the work-holder. There are numerous specific forms 20 of receding die stocks of this character. One of these forms the subject matter of Letters Patent #965,320; and the drawing shows the present invention in a form particularly applicable to this specific die stock.

25 In operating a die stock of the class which this invention is designed to improve, the cam plate is caused to, or allowed to, slowly turn as the threads are being cut, in such direction as is associated with the receding movement of the dies. When the thread-cutting operation has been completed, it is 30 desirable to move the dies outward, thereby thoroughly disengaging them from the work and to hold them out while the die stock is 35 being backed off so that the dies will not drag in the recently cut thread. It is likewise desirable that the die stock construction be such that when it has been backed off with the dies withdrawn, said dies may be 40 quickly and accurately restored to the position they should occupy for the beginning of the cutting of the thread on another piece of pipe.

The present invention is designed to facilitate 45 the complete withholding of the dies from contact with the threaded work while the die stock is being backed off, and the accurate restoration of the dies to the required position for cutting the new thread; and the invention consists in construction of a combination of parts shown in the drawing hereinafter described and definitely pointed out by the appended claims.

In the drawing Figure 1 is an end view of 50 a die stock equipped with the present invention.

tion; Fig. 2 is a side elevation of said die stock; Fig. 3 is a side elevation of certain parts shown in Fig. 2, with a cam-plate controlling post shown partly in section; Fig. 4 is an enlarged end view of a part of the die 60 stock shown in Fig. 1, when the cam-plate controlling post and the movable sleeve thereon are sectioned in the plan indicated by line 4 in Fig. 3.

Referring to parts by letters, A represents 65 a tubular die-carrier; B radially movable dies carried thereby; C the cam plate rotatably mounted on the die-carrier and engaging the dies to control their position.

D represents a tubular work-holder into 70 which the threaded extension *a* of the die-carrier screws. The work-holder is provided with the customary clamping bars F for securing said work-holder to the pipe to be threaded.

E represents a ring which is rotatably mounted upon the work-holder in a groove thereon, so as to be capable of rotating upon the work-holder but incapable of moving lengthwise thereon. Pins H fixed to the die-carrier and disposed parallel with the axis thereof, go through holes in said ring and thereby compel the ring to rotate with the die-carrier, but permit the die-carrier to screw into the work-holder.

G represents an inclined post which passes through an inclined hole *c* in an outwardly extended ear *c'* of the cam plate C. To the extent above described the die stock shown is substantially like the die stock which 90 forms the subject matter of the previously mentioned Patent #965,320.

K represents a sleeve which is mounted upon the free end of the post G so as to be capable of longitudinal movement thereon. Near its lower end it is provided with an inwardly extended shoulder *k*. A spring J lies in the space between the post and this sleeve and is compressed between the shoulder *k* and the head of a screw I which screws into the end of the post. The sleeve K has an enlarged head *k'* on its outer end, which head is concentric with the post. This head lies in the hole *c* in cam plate while the thread is being cut, and its outer inclined surface engages with the sides of said hole and thereby causes or controls the slow die-receding rotary movement of the cam plate.

Fig. 2 shows the various parts of the die 110

stock in the position which they occupy when a thread has been partly cut. When the thread has been completely cut the cam plate will have moved so far down on the head k' the cam plate can be moved under the shoulder k^2 which is afforded by the lower end of said head; and this will cause such a receding movement of the dies that they will be entirely clear of the work. When 10 now the die-carrier is unscrewed from the work-holder this cam plate engaging with this shoulder k^2 will cause the sleeve to move up on the post, (as shown in Fig. 3) the dies of course remaining in their with- 15 drawn position. When the die-carrier has been sufficiently backed off and has reached the position it must occupy to begin the cutting of the new thread, the cam plate may be turned to the left, as shown in Fig. 20 1 and Fig. 3. The upper end of the hole c will engage the side of the lower end of the head and stop the cam plate, and likewise the sleeve K , actuated by a spring J will move down on the post and in the hole c 25 to its normal position, and the cam plate and the dies will then be in the required position for beginning the cutting of a new thread.

Having thus described my invention, 30 what I claim is:

1. The combination with a die stock having a work-holder, a die-carrier which turns and moves endwise relative to the work-holder as threads are being cut, dies carried by said die carrier, a cam plate rotatably mounted on the die carrier for controlling the positions of the dies, a ring which is rotatably mounted on the work-holder but is held against longitudinal movement there- 40 on, means to compel the ring and die car- rier to rotate in unison, and a cam plate- controlling member fixed to said ring, of a cam plate-engaging device movably mounted on said cam plate-controlling mem- 45 ber and having a surface which is inclined to the axis of the die stock for engaging a part of said cam plate, and having a shoul- der beneath which the cam plate may be moved after a thread has been cut.
2. The combination with a die stock having a work-holder, a die-carrier which turns and moves endwise relative to the work-holder as threads are being cut, dies carried by said die-carrier, a cam plate rotatably 55 mounted on the die-carrier for controlling the positions of the dies, a ring which is rotatably mounted on the work-holder but is held against longitudinal movement

thereon, means to compel the ring and die carrier to rotate in unison, and a cam plate- 60 controlling member fixed to said ring, of a cam plate-engaging device movably mounted on said cam plate-controlling member and having a surface which is in- 65 clined to the axis of the die stock for engag- 70 ing a part of said cam plate, and having a shoulder beneath which the cam plate may be moved after a thread has been cut, and a spring yieldingly holding said device in working position.

3. The combination with a die stock having a work-holder, a die carrier which turns and moves endwise relative to the work-holder as threads are being cut, dies carried by said die-carrier, a cam plate rotatably 75 mounted on the die-carrier for controlling the positions of the dies, a ring which is rotatably mounted on the work-holder but is held against longitudinal movement there- 80 on, means to compel the ring and die-car- rier to rotate in unison, and an inclined post fixed to said ring, of a sleeve slidably mounted on said post and having an en- 85 larged head which passes through a hole in a part of the cam plate, the lower end of 90 said head serving as a shoulder beneath which a part of a cam plate may be moved when a thread has been cut and with which the cam plate may engage when the die- 95 carrier is being backed off of the work.

4. The combination with a die stock having a work-holder, a die carrier which turns and moves endwise relative to the work-holder as threads are being cut, dies carried by said die-carrier, a cam plate rotatably 100 mounted on the die-carrier for controlling the positions of the dies, a ring which is rotatably mounted on the work-holder but is held against longitudinal movement thereon, means to compel the ring and die-carrier to 105 rotate in unison, and a cam plate-control- 110 ling member fixed to said ring of a cam plate-engaging device movably mounted on said cam plate-controlling member and hav- ing a surface which is inclined to the axis of the die stock for engaging a part of said cam plate and having a shoulder beneath which the cam plate may be moved after a thread has been cut, and a spring yieldingly holding said sleeve in working position.

In testimony whereof, I hereunto affix my signature in the presence of two witnesses.

HERMAN W. OSTER.
